UNITED STATES PATENT OFFICE

148,896

DESIGN FOR AN ELECTRIC PLUG

Solomon Turk, Brooklyn, N. Y.

Application November 29, 1946, Serial No. 135,175

Term of patent 7 years

(Cl. D26—1)

To all whom it may concern:

Be it known that I, Solomon Turk, a citizen of the United States, residing in Brooklyn, county of Kings, State of New York, have invented a new, original, and ornamental Design for an Electric Plug, of which the following is a specification, reference being had to the accompanying drawing, forming part thereof.

Fig. 1 is a front view of the electric plug, showing my new design, said view being the same as the rear view thereof.

Fig. 2 is a side view of the electric plug as seen from the left of Fig. 1.

Fig. 3 is a side view of the electric plug as seen from the right of Fig. 1.

I claim:

The ornamental design for an electric plug, as shown and described.

SOLOMON TURK.
